TABLE LEG ADJUSTMENT

Clifford H. Green, Grand Rapids, Mich., assignor
to Automatic Musical Instrument Company,
Grand Rapids, Mich., a corporation of Michigan

Application September 27, 1933, Serial No. 691,101

3 Claims. (Cl. 45—139)

This invention relates to means for leveling tables, stands, benches, cabinets and the like, and comprises a readily operable means located in the lower end of the leg of the table or cabinet 5 for adjusting the length of the same.

The device is essentially an inverted jack screw except that the head is laterally guided and is thus supported against the side thrusts when the cabinet is shoved around on the floor; and 10 a ball detent is provided which prevents the screw from being rotated and getting out of adjustment when the cabinet is moved over the floor. Since there is always a slight eccentricity in the 15 contact, there is a tendency for the screw to turn when the cabinet is moved.

Where it is used to prevent rocking on an uneven floor, the device may be incorporated in only one of the four legs, because the three point contact will not rock, but it is seldom that the 20 fourth leg will contact simultaneously with its opposite leg; and where precise leveling is required, such as in the cabinets of automatic machines such as phonographs, the device may be incorporated in each of the four legs.

25 Main objects of invention are to provide a simple durable leveling adjustment which is capable of accommodating heavy loads and also being easily adjusted when loaded.

An illustrative embodiment of this invention 30 is shown in the accompanying drawing in which:

Fig. 1 is a perspective view of the lower portion of a cabinet;

Fig. 2 is a vertical section of one of the legs of the cabinet shown in Fig. 1; and is taken substantially on the line 2—2 of Fig. 1.

Fig. 3 is a plan section on the line 3—3 of Figure 2.

A ferrule 4 of cast metal or other suitable construction, conforming to the contour and design 40 of the cabinet 5, is fixedly mounted on the lower end on one or more of the legs 6. The ferrule has a recess 7 in the upper end which receives the end of the leg, and the lower end of the leg has a counterbore 8. The lower end of the ferrule has a cylindrical recess 9 for receiving the plug or enlarged head 10 which constitutes the floor contact member; and the upper portion 11

of the contact member 10 is reduced in diameter and threaded to screw into the solid medial portion 12 of the ferrule.

For locking the contact member against rotation, the bore or recess 9 has longitudinal grooves 14 for the engagement of a ball detent 15 which is mounted in the upper portion of the plug; and for making the adjustment, the exposed end of the plug is provided with holes for the insertion of any suitable instrument for turning the contact member and threading it up or down in the ferrule. Obviously, this construction is strong and sturdy, and well adapted for hard usage where the loads are heavy, as in radio, phonograph cabinets and the like. The adjustment is 15 very simple and easily accomplished, and it is not apt to get out of adjustment.

Having thus described an illustrative embodiment of my invention, I claim:

1. In a table leg adjustment, a ferrule fixed 20 on the end of the leg, a floor contact member comprising a cylindrical plug inserted in the lower end of the ferrule and threaded into the upper portion of the same, and a laterally projecting spring pressed detent mounted in the 25 plug for engaging the ferrule to maintain the adjustment.

2. In combination with a supporting leg, a ferrule fixed on the end of the leg, the ferrule having a longitudinally grooved recess in its 30 lower end, a floor contact member comprising a plug inserted in the recess and having a stem threaded into the upper portion of the ferrule, and a detent mounted in the plug for engaging in the grooves in said recess.

3. In a supporting leg, a ferrule fixed on the end of the leg, the ferrule having a longitudinally grooved recess in its lower end, a floor contact member comprising a plug inserted in the recess having a reduced stem threaded into the upper 40 portion of the ferrule, and a spring pressed ball detent mounted in the side of the plug for engaging in the grooves in the ferrule, the exposed end of the plug having transverse holes for receiving an instrument for rotating the plug to 45 effect the adjustment.

CLIFFORD H. GREEN.
